United States Patent

Des. 239,904
Patented May 18, 1976

239,904

PICNIC TABLE

Orville R. Bohlmann, Box 344, Denison, Iowa 51442

Filed Feb. 24, 1975, Ser. No. 552,252

Term of patent 14 years

Int. Cl. D6—05

U.S. Cl. D6—45

Fig. 1

Fig. 3

Fig. 2

Fig. 4

FIG. 1 is a perspective view of the ornamental design of my picnic table;

FIG. 2 is an enlarged top plan view thereof;

FIG. 3 is an elevational view of an end thereof, both end views being identical; and

FIG. 4 is a side elevational view of the picnic table of my invention, both side views being identical.

I claim:

The ornamental design of a picnic table, substantially as shown.
